UNITED STATES PATENT OFFICE.

HENRY M. LE DUC, OF WASHINGTON, DISTRICT OF COLUMBIA.

ANTIFRICTION-ROLLER.

SPECIFICATION forming part of Letters Patent No. 624,506, dated May 9, 1899.

Application filed December 1, 1897. Serial No. 660,383. (No model.)

To all whom it may concern:

Be it known that I, HENRY M. LE DUC, a citizen of the United States, residing at Washington, in the District of Columbia, have invented certain new and useful Improvements in Antifriction-Rollers for Cars, Bicycles, and Vehicles; and I do hereby declare the following to be a full, clear, and exact description of the invention, such as will enable others skilled in the art to which it appertains to make and use the same.

My invention has reference to improvements in antifriction-rollers for bearings, in combination with revolving and stationary shafts, axles, or journals for various purposes; and it consists of certain novel features of construction, which will be hereinafter fully described in the specification and pointed out in the claim.

20 The object of the present invention is to provide cheap, economical, and efficient means for overcoming friction in bearings.

The present invention is so constructed and arranged that all abrading friction is overcome, as the contacting surfaces of the friction and separating rolls move in opposite directions by rolling contact. To overcome end friction of the rolls against their confined casing or shell, a central rib is cast integral with the hub of the revolving wheel, said rib affording means for a central groove turned in the periphery of each roll to lie within the circumference of said rolls, thus holding them free from the walls of the casing or shell of the wheel. The grooves in the rolls referred to are of a greater depth than the internal projecting rib referred to; otherwise there would be undue friction between the periphery of the rib and the bottom of the grooves in said rolls, as the surface speed in both varies in the ratio of the radial distance between the periphery of the rolls and bottom of the grooves in said rolls.

To more fully elucidate the device, I will proceed to describe the drawings, in which—

Figure 1 represents a longitudinal section of my improved device which is adapted for a bicycle. Fig. 2 represents in side elevation my improved device with the cover removed to exhibit the rollers. Fig. 3 represents in detail a portion of the hub-rim with the internal rib, which is provided with a gap or

opening for assembling the rolls within a hub or casing.

A indicates a sleeve having the free ends 55 of the same threaded to receive hubs A' A², said hubs being provided with ordinary wire spokes a². Passing centrally through said sleeve A is an axle B, which terminates in the hub A', which will be hereinafter more fully 60 set forth. Said hubs A' and A² are provided with a chamber C for receiving friction-rolls D and guide or separating rolls E.

Within each chamber and integral with the same is a rib c, which fits into a groove d, 65 formed in each of the rolls D, previously referred to. The separating-rolls E are also provided with grooves e, which register with the groove in each of rolls D. Said separating-rolls E are provided with a pintle or journal e' on each end and which travel in annular grooves in the walls or sides of the hubs A' and A², respectively. Each hub A' and A² is provided with a cover a'. In Fig. 1 lock-nuts F are indicated, the inner nut being so 75 constructed as to exclude dust from the friction-rolls through the medium of felt dust-rings f.

Shaft or axle B is provided with ribs b to prevent end thrust of the axle, as the friction-rolls are held in position by the internal rib c in each hub. Consequently the grooves in said rolls act similar to a solid shoulder for said ribs b to abut against. The gaps formed in said ribs c are provided with plates or plugs 85 G and set-screws g, the latter for securing them to the hubs A' and A² when the friction-rolls are assembled in working position.

What I desire to claim is—

An axle having ribs thereon, grooved friction-rolls adapted to be guided by said ribs, hubs having projecting ribs therein and also for guiding said friction-rolls, there being a gap in said ribs for assembling said friction-rolls, in combination with a plug for closing 95 said gap when said friction-rolls are assembled, and the means for securing said plug, substantially as described.

In testimony whereof I affix my signature in presence of two witnesses.

HENRY M. LE DUC.
